UNITED STATES PATENT OFFICE.

GEORGE ERZ, OF LYNDEN, WASHINGTON.

WINDOW-LATCH.

1,072,593.

Specification of Letters Patent.

Patented Sept. 9, 1913.

Application filed April 21, 1911. Serial No. 622,612.

To all whom it may concern:

Be it known that I, GEORGE ERZ, a citizen of the United States, and a resident of Lynden, in the county of Whatcom and State 5 of Washington, have invented a new and Improved Window-Latch, of which the following is a full, clear, and exact description.

My invention is an improvement in window latches, and has for its object the provision of a simple, compact automatic device 10 of the character specified which may be placed at either side of the window and which will be inconspicuous when in place.

In the drawings:—Figure 1 is a front 15 view of the improvement, showing the latch extended with the cover plate removed; Fig. 2 is a similar view showing the latch withdrawn; Fig. 3 is a similar view showing the latch partially extended; Fig. 4 is a 20 section on the line 4—4 of Fig. 1; Fig. 5 is a face view of the escutcheon with the handle removed; Fig. 6 is a similar view with the handle in place; and Fig. 7 is a section on the line 7—7 of Fig. 1.

The present embodiment of the invention 25 comprises a casing consisting of plates 1 and 2 spaced apart by a block 3 and held together by screws 4 which pass through the plates and the block. The block is provided 30 with a central recess 5 and with a longitudinal passage 6 intersecting the recess and opening at one end of the block. The said end is covered by a shield plate 7^a. A latch 7 is slidable in the passage 6, and the upper 35 corner of the outer end of the latch is beveled at 8. The latch is provided with a transverse slot 9 and with a recess 10 in one side wall extending at right-angles to the slot and intersecting the same. The latch 40 is normally pressed outwardly by a coil spring 11 seated in the inner end of the passage 6 and bearing against the inner end of the latch. A plate 12 is provided for attachment to the window casing and the said 45 plate is equipped with ratchet teeth 13. The teeth face upward so that when the window is lifted the beveled corner of the latch will engage the inclined faces 14 of the teeth. When however the window is lowered, the 50 lower edge of the latch engages the horizontal faces 15 of the teeth and hold the latch and window in adjusted position.

An operating cam 16 is arranged in the opening 10, and the said cam is provided 55 with an eccentric portion 17 having one edge 18 plain and the other edge provided with

ratchet teeth 19. That portion of the latch at each end of the opening 10 is provided with spaced notches 20 for engagement by the point of the eccentric portion of the cam 60 to hold the said latch withdrawn or extended. A key 21 is provided for operating the cam and the cam has a central opening for receiving the key. The outer end 22 of the key is polygonal in cross section and is 65 provided with a cross head 23 secured to the key by a pin 24. The head is arched longitudinally and is arranged with its ends in contact with an escutcheon 25 circular in form and having openings 26 for receiving 70 screws or nails to hold it in place. The escutcheon is also provided with a central opening 27 for the key and with indications or guides in the form of legends 28. The said guides indicate the positions to be assumed by the head to hold the latch open, closed, or in the position of Fig. 3. The head is provided at one end with a point 29 acting as an indicator, and at the other end with a claw 30 to distinguish the said end 80 from the end 29. The cam may be turned by the key and when so turned will extend or withdraw the latch bar and the said bar may be locked in either position by engaging the point with a notch. 85

The curved edge 18 of the cam 16 is adapted to engage the rear wall of the recess 10 in the latch 7 to retract the latch and to put the spring 11 under compression. If desired, the point of the cam may be engaged 90 in the teeth which are formed in the rear wall of the recess 10, to hold the latch releasably in a retracted position. Likewise, the point of the cam may be engaged in the teeth which are formed in the forward wall 95 of the recess 10 in the latch 7, to prevent rearward movement of the latch beyond a predetermined point represented by the extremity of the cam. At times, the point of the cam cannot be engaged in the notches 100 which are formed in the forward wall of the recess 10 in the latch 7, because the plate 12 may be disposed so close to the shield plate 7^a as to prevent this operation. Under the circumstances last above pointed out, the 105 teeth 19 on the cam 16 may be brought into co-operation with the lowermost tooth which is formed on the forward wall of the recess 10 in the latch.

I claim:—

In a device of the class described, a casing; a latch mounted in the casing for right-

line movement, the latch having a recess and there being teeth formed in the latch in the forward and rear walls of the recess; spring means for advancing the latch; a shaft journaled in the casing; and a cam secured to the shaft, the cam being movable in the recess, the cam having a curved surface adapted to engage the rear wall of the recess, to retract the latch against the action of the spring means, the cam having a point adapted to engage detachably in the teeth of the rear wall to hold the latch retracted, and to engage the teeth of the forward wall detachably, thereby to prevent rearward movement of the latch; the cam having teeth

in one of its edges, adapted to coöperate detachably with the lowermost tooth of the forward wall to prevent a retraction of the latch when the same cannot be advanced sufficiently to permit the point of the cam 20 to coöperate with the teeth of the forward wall.

In testimony whereof I have signed my name to this specification in the presence of two subscribing witnesses.

GEORGE ERZ.
